United States Patent Office.

WILLIAM A. FENN, OF WOLCOTT, NEW YORK.

Letters Patent No. 70,709, dated November 12, 1867.

IMPROVED SALT-SIFTER.

The Schedule referred to in these Letters Patent and making part of the same.

TO ALL WHOM IT MAY CONCERN:

Be it known that I, WILLIAM A. FENN, of Wolcott, in the county of Wayne, and State of New York, have invented a new Improvement in Salt-Sifter; and I do hereby declare the following, when taken in connection with the accompanying drawings, and the letters of reference marked thereon, to be a full, clear, and exact description of the same, and which said drawings constitute part of this specification, and represent, in—

Figure 1, a side view,

Figure 2 a top view, and in

Figure 3 a vertical central section.

This invention is designed for table-salts, or peppers, or similar articles, to finely sift the contents, the object being to prevent the stoppage or to force the material through the sifter, and consists in the arrangement of a perforated plate in the top of a bottle or box, so as to be turned partially around and returned, the inner surface being roughened so as to scrape or agitate the contents, and cause the same to fall through the perforations.

To enable others to construct my improvement, I will proceed to describe the same as illustrated in the accompanying drawings.

A is an ordinary caster-bottle, provided with a ring, B, upon its top. C, a perforated plate, held within the upper edge of the ring B, and so as to permit the turning of the plate from right to left and returned, as denoted in fig. 3. The plate C is best formed by making the perforations from the outside in, which naturally leaves a burr upon the under side, which acts as a grater when moved so as to rub upon the contents of the bottle. A handle, D, is attached to the said plate by which to thus move it.

When any portion of the contents of the bottle is required for use, invert the bottle and turn the plate back and forth, so that the contents, lying upon the plate, will be grated or agitated so as to pass out through the perforations in the plate. For greater convenience in use, I place upon the neck of the bottle a spring, d, so as to bear against the handle D, or in other convenient position or form of spring, so that when the plate is turned, as to the position in red, fig. 3; the spring will cause its return.

This invention, though designed with special reference to table-caster bottles, is equally applicable to other uses.

Having, therefore, thus fully described my invention, what I claim as new and useful, and desire to secure by Letters Patent, is—

1. The arrangement of the plate C, in combination with the bottle or case A, so as to operate in the manner described.
2. In combination with the above, I claim the arrangement of a spring, so as to return the plate, substantially as herein set forth.
